PROCEDURE OF COKING PITCH AND COAL
IN A BY-PRODUCT COKE OVEN BATTERYWilliam Tiddy, Scarsdale, N. Y., assignor to
Semet-Solvay Engineering Corporation, New
York, N. Y., a corporation of New York

Application October 30, 1930. Serial No. 492,178

3 Claims. (Cl. 202—3)

This invention relates to coking of pitch, and more particularly to the distillation of the tar produced at a coke oven plant with production of pitch and distillate oils and the coking of the pitch thus produced in one or more of the coking chambers of the coke oven battery. This invention is in the nature of an improvement on the invention disclosed in the pending application of Stuart Parmelee Miller, Serial No. 413,253, filed

10 December 11, 1929.

One object of this invention is to provide a process for simultaneously coking coal and pitch in the coking chambers of a coke oven battery, the coal being coked in some of the chambers, 15 pitch in others, the distillate gases collected, tar removed therefrom, the tar distilled to pitch by contact with hot gases from the coking chambers, and the resultant pitch coked in some of the coking chambers. Other objects and advantages will appear from the following detailed description.

The process of this invention can be carried out in ordinary coke oven batteries such as the horizontal flue type batteries, vertical flue type batteries, or batteries involving alternate heating walls and coking chambers, the heating walls having no defined flue structure, with but slight alterations and the addition of a small amount of equipment to such batteries. This invention includes such modified coke oven batteries. I have discovered that lining the interior of one or more coking chambers of a coke oven battery with a high temperature heat resisting metal, 30 adapts such coke oven batteries to the efficient coking of pitch.

At the temperatures prevailing in the coking chambers during coking, pitch is fluid and seeps through the refractory material of the chambers into the flues and regenerators soon interfering with and preventing satisfactory operation of the battery. Coking chambers constructed in accordance with this invention are not subject to the seepage and leakage of pitch through the refractory brickwork which occurs when coking 40 pitch in the usual refractory brickwork structures.

The coking chambers may be equipped with inlets for a gas, chemically inert with respect to the pitch, such as nitrogen or other inert gas, preferably steam, which is introduced into the chamber during the coking and prevents the foaming and boiling over characteristics encountered in the coking of pitch.

In applying this invention to existing coke oven batteries or in the building of new batteries, preferably, but not necessarily, only a portion of the

coking chambers are provided with a lining of high temperature heat resisting metal and inlets for the introduction of inert gas. The unlined coking chambers of such batteries may be used to coke coal, tar being recovered from the distillation gases and distilled at the plant in a tar still, such as disclosed in the aforementioned pending application, the resulting pitch being charged into the lined coking chambers and the distillation products from the pitch admixed with those from the coal and utilized for the distillation of the tar in the still.

In the accompanying drawings, forming a part of this specification, and showing, for purposes of exemplification, a preferred form of this invention but without limiting the claimed invention to such illustrative instances—

Fig. 1 is a fragmentary diagrammatic plan view of a coke oven battery equipped to carry out this invention;

Fig. 2 is a fragmentary elevation, partly in section, showing the tar still with the pitch feed to the three ovens at one end of the coke oven battery;

Fig. 3 is a section through the tar still in the plane indicated by the line 3—3 of Fig. 2; and

Fig. 4 is a fragmentary vertical section through a coking chamber embodying this invention, the regenerators beneath the coking chambers, which are of usual design, and per se form no part of this invention being omitted for the sake of clearness.

In the preferred embodiment illustrated in the drawings, the invention is shown incorporated in a coke oven battery of the horizontal flue type and the present description will be confined to the present illustrated embodiment of the invention in such oven battery. It will be noted, however, that the novel features and improvements are susceptible to other applications, such, for example, as vertical flue coke oven batteries or coke oven batteries involving alternate coking chambers and heating walls which have no well defined flues. Hence, the scope of this invention is not confined to the embodiment herein described.

The coking chambers of the coke oven battery connect in the usual way with the collector main 6 through uptake pipes 7. The oven battery as shown in Fig. 2 involves alternate coking chambers 15 and heating walls 16, the heating walls in the embodiment of the invention shown in Fig. 2 being constituted of horizontal zigzag series-connected combustion flues. Regulators, not shown in the drawings, extend cross-

wise of the battery beneath the coking chambers and supply the flues with preheated air. Fuel gas is introduced directly into the flues through the usual burners, burning therein, the 5 products of combustion leaving the flues through the outflow regenerators. This operation, as customary, is periodically reversed, the inflow regenerators becoming outflow regenerators and serving to extract heat from the products of 10 combustion, and the outflow regenerators becoming inflow regenerators and imparting the heat retained by the checker-brick to the air fed therethrough into the flues.

Means is provided for spraying the gases in 15 the uptake pipes and in the collector main with ammonia liquor from the line 8. The collector main 6 may connect with about 20 ovens in one section of a battery of, for example, 60 ovens. The gases pass from the collector main 6 20 through the cross-over main 9 to condensers 10. In the condensers 10, the gases are sprayed with ammonia liquor. The tarry oils and ammonia liquor are drawn off from the condensers to one or more decanters 11. From the decanters, tarry 25 oils are collected in storage tanks 12 and ammonia liquor is separately collected in ammonia liquor storage tanks 12'. An exhauster 13 is provided for drawing the gases through the system.

The three coking chambers 15 (Fig. 2), hereinafter more fully described, located at the end of the coke oven battery adjacent the pinion wall 17, are connected through the usual uptake pipes 7 with the collector main 6. Tar from the gases coming off from the coking chambers 15 30 is preferably distilled with the tar from the coal distillation gases coming from the other ovens. The tar and ammonia liquor collected in main 6 are drawn off through the collector main at the end of the oven adjacent to the pinion wall into 35 the decanter 18. The heavy tar and ammonia liquor are separately drawn off from the decanter 18 and separately passed to storage tanks 19 and 20 respectively.

Either the tarry oils from the tanks 12 or the 40 heavier tar in the tanks 19, or a blend of both of these tars or tar otherwise derived may be distilled in still 25. Any tar produced in connection with the operation of a gas producer or water gas machine employed for making gas for heating the ovens, may be added to the tar to be distilled in the still.

The tar still is indicated at 25. It connects through the hot gas header 26 with uptake pipes 27 on a number of the coking chambers. By a 50 proper manipulation of the valves on the uptake pipes 27 and the uptake pipes 7 on these coking chambers, the hot gases from the chambers may be diverted either to the collector main 6 or through the hot gas header 26 into the still 25.

60 A roll 28 is rotatably mounted in the still 25. This roll is adapted to be driven at a high speed, for example, 900 to 1200 r. p. m., by the motor 29. Rapid rotation of this roll throws a fine intense spray of tar into the hot gases thereby exposing a large surface of the tar to the distilling effect of the hot gases, whereby distillation is rapidly and efficiently effected without any considerable decomposition of the tar. The fine intense spray of tar simultaneously scrubs the 70 gases, removing entrained impurities present in the gases. The hot gases leave the still 25 enriched in oil vapors and substantially free from entrained impurities through the scrubber 25'. Preferably, the tar to be distilled is supplied to this scrubber through the line 30. Baffling means

80 31 and 32 are provided in the scrubber tower 25' to remove entrained particles of tar spray from the gases. The tar sprayed into the gases passing up through the scrubber 25' is partially distilled and the semi-pitch produced passes through the line 33 into the end of the tar still at which the hot gases enter. In the still 25, the semi-pitch is distilled to a pitch of high melting point. The pitch is drawn off from the still through the coke trap 34 and the levelling arm 35, into the pitch bay 44. The pitch is advantageously distilled to a high melting point, for example, 400° F. or higher.

85 90 The hot gases and vapors from the scrubber 25' pass through the main 36 to a heat interchanger 37 in which they are brought into indirect heat interchange relation with the tar to be distilled. The tar is thus preheated and heat economy is effected. Heavy oils are separated from the gases and collected in the storage tank 38. The 95 gases then pass through a further condenser which may be a direct condenser 39 in which the gases are sprayed with water or ammonia liquor from the line 40. This condenser drains into the decanter 41 and separate means are provided at 100 42 and 43 for receiving the ammonia liquor and lighter oils from the decanter 41.

105 110 The pitch may be supplied directly from the tar still 25 to the coking chambers 15 or it may be first cooled and solidified and supplied to the ovens in solid form, or according to the preferred embodiment shown in the drawings, it is first collected in the pitch bay 44 where it is maintained in a hot fluid condition by heavy insulation or by indirect contact with hot flue gases. 115 Bay 44 may serve as an accumulator for the pitch which is to be supplied to the ovens. While a portion of the pitch charge is being coked, sufficient pitch for the next charge accumulates in the bay 44.

115 120 In accordance with this invention, the interior walls of each of the coking chambers 15 are formed with a lining of high temperature heat resisting metal, such, for example, as an alloy containing nickel. One example of a suitable alloy is the alloy known commercially as "Fahrite" which contains 40% nickel and 20% chromium and will withstand temperatures of 2000° F. This lining is indicated by the reference numerals 51 in Figs. 2 and 4. If desired, the refractory 125 brickwork of the doors extending within the coking chambers may also be lined with high temperature heat resisting metal as indicated at 52. Although three coking chambers 15 are shown equipped for coking pitch and the remaining 130 ovens 15' (Fig. 1) are not provided with a high temperature heat resisting metal lining and are adapted to be used for coking coal, it will be understood that the number of coking chambers equipped with this invention may be modified in 135 accordance with operating conditions at the coke oven battery. A line 45 leads from the pitch bay 44 and is arranged to discharge pitch into any desired coking chamber 15. Suitable valve means indicated at 47 is provided for controlling the 140 feed of pitch through the line 45 into the coking chambers. Pipe 45 communicates with pipes 54 extending above the battery longitudinally of the coking chambers. Each pipe 54 is provided with a plurality of inlet pipes 55 which extend through 145 the coking chamber top into the coking chamber and through which the pitch is fed to the coking chambers. Valve controlled lines 53 and 56 on opposite sides of the batteries are connected with each of the pipes 54. Valve controlled pipes 57 150

extend through the doors of the collecting chamber. Preferably, the pipes 57 are provided with flexible connections to a main communicating with the source of inert gas. The flexible connections of pipes 57 permit movement of the doors.

As well known, pitch when subjected to heat to form coke starts to boil and foam, accompanied by a sharp rise in level of the pitch, 10 finally reaching a maximum level, at which point the level recedes and continues to do so until the level in some cases is below the original level of the melted pitch. I have found that the foaming and boiling over tendencies of the pitch during 15 coking in a coke oven battery can be retarded and eliminated to an extent permitting efficient use of the capacity of the coking chamber by introducing an inert gas, such as nitrogen or preferably steam, during the coking of the pitch. The 20 inert gas is introduced into the coking chamber 15 during the coking of the pitch through the pipes 56, 53, 54, 55 and 57, the inert gas in passing through pipes 54 and 55 removing residual pitch therein and thus preventing clogging of 25 these pipes, at the same time conserving the pitch since it passes with the inert gas into the coking chambers. Any inert gas may be used, the introduction thereof into the top of the chamber acting mechanically to prevent foaming 30 of the pitch charge. Steam is particularly suitable for this purpose as it does not retard the coking operation but assists same since it aids in driving off the volatiles and assists in the passage of the volatiles out of the coking chamber, 35 prevents foaming and involves no difficulties in the handling of the mixture of volatiles and steam.

After the coking chambers have been charged and the coking operation is completed, the charge 40 of coke from the ovens is removed in any suitable manner. The pusher which operates on tracks (not shown) and which is employed for pushing the coke resulting from the distillation of coal in the balance of the ovens of the battery, 45 may be employed for pushing the coke from the coking chamber 15. The coke car which operates on tracks at the opposite side of the battery may be employed for receiving the coke as it is pushed from the chambers 15. The coke 50 quenching equipment employed for cooling the coke produced from the coal may be employed for cooling the pitch coke. In this way the cost of the original equipment is kept at a minimum by employing the same means for handling the coke 55 produced from coal and the coke produced from pitch.

The invention as hereinabove disclosed is embodied in a particular form of construction but it may be variously embodied within the scope of 60 the following claims.

I claim:

1. The method of operating a coke oven battery, involving coking chambers and heating

walls therefor arranged side by side in a row, the heating walls being constituted of combustion flues, the walls of some of the coking chambers being lined with a high temperature heat resistant metal while the remaining coking chambers are unlined and are composed of refractory brickwork, which comprises coking coal in the unlined coking chambers, coking pitch in the lined coking chambers to form pitch coke, withdrawing the hot gases resulting from the coking of the coal and the pitch, admixing these hot gases, removing tar from the admixed hot gases, distilling the tar removed from said admixed hot gases by contacting the tar with hot gases from the coking chambers so as to form a pitch residue, and coking the pitch residue in the lined coking chambers to produce pitch coke.

2. The method of operating a coke oven battery involving coking chambers and heating walls therefor, arranged side by side in a row in alternate relation, the heating walls being constituted of combustion flues, the walls of some of the coking chambers being lined with a high temperature heat-resistant metal while the walls of the remaining coking chambers are unlined and 100 are composed of refractory brickwork which comprises: (1) coking coal in the unlined coking chambers; (2) coking pitch obtained by step (5), hereinafter recited, in the lined coking chambers simultaneously with the coking of the coal; (3) 105 collecting the distillate gases from the coking of the pitch and the distillate gases from the coking of the coal and admixing said gases; (4) removing tar from the distillate gases; and (5) 110 distilling the tar removed from the distillation gases so as to form distillate oils and a pitch residue by contacting the tar with said admixed gases.

3. The method of operating a coke oven battery involving coking chambers and heating 115 walls therefor, arranged side by side in a row in alternate relation, the heating walls being constituted of combustion flues, the walls of some of the coking chambers being lined with a high temperature heat-resistant metal while the walls 120 of the remaining coking chambers are unlined and are composed of refractory brickwork, which comprises: (1) coking coal in the unlined coking chambers; (2) coking pitch obtained by step (5), hereinafter recited, in the lined coking chambers 125 simultaneously with the coking of the coal; (3) collecting the distillate gases from the coking of the pitch and the distillate gases from the coking of the coal and admixing said gases; (4) removing tar from the distillate gases; (5) 130 distilling the tar removed from the distillation gases so as to form distillate oils and a pitch residue by contacting the tar with said admixed gases; and (6) introducing inert gas into the lined coking chambers during the coking of the pitch to prevent 135 foaming and boiling over of said pitch.

WILLIAM TIDDY.
